(57) **CLAIM**

The ornamental design for an LED front panel for refrigerator as shown and described.

DESCRIPTION

FIG. 1 is a front perspective view of an LED front panel for refrigerator showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a partial enlarged view of portion 9 in FIG. 2;

FIG. 10 is a partial enlarged view of portion 10 in FIG. 2;

FIG. 11 is a front perspective view of the LED front panel for refrigerator, shown in a state of use;

FIG. 12 is a rear perspective view thereof;

FIG. 13 is a front elevation view thereof;

FIG. 14 is a rear elevation view thereof;

FIG. 15 is a left-side elevation view thereof;

FIG. 16 is a right-side elevation view thereof;

FIG. 17 is a top plan view thereof; and,

FIG. 18 is a bottom plan view thereof.

A characteristic feature of the claimed design lies in the front panel having different color lights emitted from the LED mounted on the bottom of the LED board. The portion of the LED front panel shown in a pattern of stipple in FIGS. 11 and 13 illustrate areas of contrasting appearance. The colors embodied in the panel cover are not limited to a specific color or arrangement of colors. The dot-dot-dash broken lines shown in FIGS. 2, 9 and 10 indicate the enlargement areas and form no part of the claimed design.
